SURGICAL FORCEPS

John L. Marco, Kew Gardens, N. Y., assignor to
Goodman-Kleiner Company, Inc., New York,
N. Y., a corporation of New York

Application June 10, 1952, Serial No. 292,622.

4 Claims. (Cl. 128—361)

1 My invention relates to an extractor particularly adapted for the guiding of a fetal head through the incision made when a caesarian section is performed.

An important object of my invention is the provision of an instrument which may be folded so that the handle is completely out of the way when the blade of the instrument is inserted in an incision yet locks automatically into a single shaft after implantation all with a single pivot.

Other advantages will be apparent from the specification and drawings, in which:

Fig. 1 is a perspective view of the forceps;

Fig. 2 is a fragmentary partially broken away section showing the joint between the handle portion and the forceps proper;

Fig. 3 is a view similar to Fig. 2 but with the joint in closed position;

Fig. 4 is a cross sectional view along line 4—4 of Fig. 3;

Fig. 5 shows the instrument being inserted around the head of a fetus;

Fig. 6 is a view similar to Fig. 5 but with the instrument in position for lifting the head of the fetus.

Referring to the drawings, 1 represents a single fenestrated or spoon-like forceps blade or base with an open center shaped in an exaggerated cephalic curve and formed of relatively thin yet rigid material, preferably metal, having an upper shaft 2. The upper end of shaft 2 is split at 3 to form guide arms 5' and 5 for retention of the flat swivel projection 6 on the upper shaft 7. The flat swivel projection 6 is held pivotally within the guide arms 5' and 5 by means of a swivel pin 8 passing through arms 5' and 5 and through projection 6 as shown by Figs. 1 through 4.

The projection 6 is pivoted considerably below the top of the arms 5' and 5 and is constructed with an indentation 9 so that the upper and lower shafts 2 and 7 are allowed to rotate on each other in one direction only by reason of the fact that indentation 9 makes contact with stop pin 10 at the uppermost portion of arms 5' and 5. It will be seen by Fig. 3 that because of the indentation 9 the shaft 7 may swing into alignment with shaft 2 but may go no further because of stop pin 10.

In order that shafts 2 and 7 may be locked in alignment I provide for a collar 11 restricted in its upward movement by a stop lug 12 and restricted in its downward movement by the head 13 of swivel pin 8. It will be seen that when shaft 7 is brought into alignment with shaft 2 the collar 11 will drop and cover the joint be-

tween shaft 7 and shaft 2, effectively locking them in aligned position.

In order that shaft 7 may fold back more than 90° I provide a notch 14 in the arms 5' and 5. This notch or indentation 14 is necessary for the use of the instrument and is shown graphically by Fig. 5, and will be explained in more detail later.

The shaft 7 above the stop lug 12 is curved inwardly at 15 to a point directly above the medial point of the forceps 1 and then is curved outwardly at 16 to terminate in a handle 17. In this connection it will be apparent to those skilled in the art that a lifting of the handle 17, when shafts 2 and 7 are locked in alignment, will create a balanced pull at the center of the forceps blade, as indicated by dotted line arrow in Fig. 6.

Operation

An incision is made through the abdominal wall and the instrument in folded position, as shown by Fig. 5, is introduced into the cavity around the head of the fetus. It is extremely necessary in inserting the forceps blade that the handle be completely out of the way and therefore folded back at more than a 90° angle in order that the blade be allowed to completely enter the cavity through the incision. This has been provided for by the notch 14 in the guide arms 5' and 5, and the more than 90° foldback of the handle 17 and shaft 7 allows for the introduction of the instrument which would otherwise be impossible due to the obstructing pregnant uterus in the anterior abdominal wall as illustrated in Figs. 5 and 6.

When the instrument has cradled the cranium of the fetus the handle 17 is lifted upward allowing the collar 11 to drop by gravity and lock the shafts 2 and 7 in position as soon as they come into alignment, at which time further lifting of the handle 17 will exert a pull directly upwards as shown by the dotted line arrow of Fig. 6, lifting the head of the fetus through the incision without injury since the entire cranium is cradled in the spoon-like forceps blade, and all weight is evenly distributed.

It will be understood that all of the parts of the instrument are made smooth and of as few pieces as possible, since such a type of manufacture greatly decreases the time necessary for actual application without causing trauma to delicate tissue.

Various changes in the structure of my invention will be apparent to those skilled in the art without departing from the scope of my invention in which I claim:

I claim:

1. In a surgical instrument of the character described, an open spoon-like base conforming approximately to the shape of an infant's cranium, a shaft leading from said base and split at its uppermost portion, a second shaft bent inwardly disposed above said base and pivotally attached within the split of said first named shaft, said pivot being positioned substantially below the terminus of said first named shaft, a collar surrounding said second named shaft and adapted to move over the juncture between said shafts and hold them in rigid relationship the one with the other.

2. In a surgical instrument of the character described, an open spoon-like base conforming approximately to the shape of an infant's cranium, a shaft leading from said base and split at its uppermost portion, a second shaft bent inwardly and outwardly terminating in a handle said outward bend disposed above the central portion of said base, said second named shaft being pivotally attached to said first named shaft and embraced within the split of said first named shaft said pivot being positioned substantially below the terminus of said first named shaft, a collar surrounding said second named shaft and adapted to move over the juncture between said shafts and hold them in rigid relationship the one with the other.

3. In a surgical instrument of the character described, an open spoon-like base conforming approximately to the shape of an infant's cranium, a shaft leading from said base and split at its uppermost portion, a second shaft bent inwardly then outwardly terminating in a handle said outward bend disposed above the central portion of said base and said second named shaft being pivotally attached to said first named shaft and embraced within the split of said first named shaft said pivot being positioned

5 substantially below the terminus of said first named shaft, a collar surrounding said second named shaft and adapted to move over the juncture between said shafts and hold them in rigid relationship the one with the other, said collar being restricted in movement over said shafts by stop members on said shafts.

10 4. In a surgical instrument of the character described, an open spoon-like base conforming approximately to the shape of an infant's cranium, a shaft leading from said base split at its uppermost portion, a second shaft bent inwardly then outwardly terminating in a handle, said outward bend disposed above the center of gravity of said base and said second named shaft attached to said first named shaft and embraced within the split of said first named shaft, said pivot being positioned substantially below the terminus of said first named shaft, a stop pin on said first named shaft cooperating with a recess on said second named shaft whereby said shafts may pivot in one direction only, a collar slidably mounted on said second named shaft adapted to move over the juncture between said shafts and hold them in rigid relationship the one with the other when they are in alignment.
